(57) **CLAIM**

The ornamental design for a media device control box, as shown and described.

DESCRIPTION

FIG. 1 is a front perspective view of a media device control box showing our new design;

FIG. 2 is a front view thereof;

FIG. 3 is a first side view thereof;

FIG. 4 is a second, opposing side view thereof;

FIG. 5 is a rear view thereof;

FIG. 6 is a top view thereof; and,

FIG. 7 is a bottom view thereof.

The broken lines in the drawing are for the purpose of illustrating unclaimed portions of the LED display module and form no part of the claimed design.
